HYDRAULIC BOOM AND SUPPORT UNIT FOR VEHICLES

John L. Grove, 171 Apple Drive, Greencastle, Pa.

Filed July 2, 1965, Ser. No. 86,005

Term of patent 14 years

(Cl. D14—3)

FIG.2

FIG.5

FIG.6

FIG. 1 is a side view of a hydraulic boom and support unit for vehicles showing my new design with the boom in traveling position;

FIG. 2 is a top plan view thereof;

FIG. 3 is a side elevational view of the hydraulic boom and support unit shown in FIG. 1 with the hydraulic boom in elevated and extended position;

FIG. 4 is a side elevational view of the opposite side of the hydraulic boom and support unit shown in FIG. 3;

FIG. 5 is a view looking at the right-hand side of the hydraulic boom and support unit shown in FIG. 4; and

FIG. 6 is a view looking at the left-hand side of the hydraulic boom and support unit shown in FIG. 4.

The dominant features of my new design are shown in solid lines in the drawings and the vehicle disclosed by means of broken lines on the drawings is shown for illustrative purposes only.

I claim:

The ornamental design for a hydraulic boom and support unit for vehicles, substantially as shown and described.
